JERSEY

MAGNETIC CORE

Application filed January 3, 1931. Serial No. 506,380.

This invention relates to magnetic core members for current transformers or other electrical apparatus, and has for one of its objects the provision of a magnetic core which 5 can be easily and cheaply made and which will be strong and efficient.

Other objects and advantages will appear from the following description.

The invention is exemplified by the combination and arrangement of parts shown in the accompanying drawing and described in the following specification, and it is more particularly pointed out in the appended 10 claims.

15 In the drawing:

Fig. 1 is a fragmentary longitudinal section of a portion of a core showing one embodiment of the invention.

20 Fig. 2 is a plan of a core showing another modification.

Fig. 3 is a fragmentary section on line 3—3 of Fig. 2.

Fig. 4 is a plan of a core showing a different modification.

25 Fig. 5 is a section on line 5—5 of Fig. 4.

Fig. 6 is a view similar to Fig. 3 showing another modification of the invention.

Fig. 7 is a view similar to Fig. 2 showing a different form of the invention.

30 Figs. 8 and 9 are sectional views showing details.

Fig. 10 is a section on an enlarged scale of a portion of Fig. 7.

In the manufacture of current transformers, it has heretofore been customary to use 35 circular sheet metal punchings from which to build up the core. Transformers with cores made of these punchings are not only costly but in some instances do not have satisfactory 40 electrical characteristics.

The present invention is especially applicable to the magnetic core for a current transformer, such as that of my prior Patent No. 1,723,000, in which the primary makes one 45 or more turns around the core. The effective lines of force not only travel through the iron but through an air path as well. Where the core of this type is used in bushings as shown in my patent referred to above, it is 50 desirable to obtain mechanical strength and

rigidity in the core. This can be obtained by wrapping or rolling the core of suitable sheet iron. By this manner of construction, a short-circuit turn will be created in the core if electrical contact is made between 55 successive turns. It is therefore necessary to prevent a short circuit turn by interposing insulation between the layers of sheet metal as shown at 10 in Fig. 10. The insulation may be paper or other suitable material 60 interposed between the layers of sheet iron 11.

If several sheets 11 are wound together, with two or more layers 10 of insulation in the group, an electrical break-down will have to 65 take place through all of the insulating sheets before a short-circuit turn will result. It is, therefore, advisable to wind several sheets at the same time as the ratio of magnetic material to insulation may be increased but in addition the probability of a break-down causing a short-circuit turn will be greatly reduced. This method of construction makes it possible to use fewer layers of insulation 70 so that greater latitude is permitted in the insulation itself. By using an insulation such as asbestos or mica, which will withstand heat, the core may be annealed after wrapping.

75 In order to reduce eddy currents, the several sheets may be coated with a varnish which contains a residue or material which will provide sufficient insulation to reduce eddy currents after the baking out. A material which will readily stand annealing temperature may be provided by the introduction of finely ground earth or silica into the varnish or binder used for holding the material 80 during the forming operation.

85 The core may be made in various ways, as from bundles of magnetic wire or rods, as well as from sheets. After the core is formed, it may be annealed and then impregnated with a suitable oil, varnish or enamel and then baked or cured. The hardening of the 90 coating material, together with the arrangement, will provide a very solid core which will give the necessary rigidity for the support of the primary winding and insulating 95 baffles when desired.

- Since an appreciable part of the magnetic path is through the air, it is evident that the magnetic core may be made up in sections if desired without seriously affecting the magnetic reluctance of the circuit. The core may be built up by winding strips of magnetic material in a plurality of helical layers in any suitable form. The strips may be offset in the different layers, as shown at 20 in Fig. 1. 5
- 10 A layer of insulation 14 may be formed on the outside of the core in any suitable way as by winding with varnished cambric. By staggering the turns in different layers, as shown in Fig. 1, a strong mechanical construction is obtained and a long magnetic core may be provided with a rather narrow width of sheet 20. Owing to the stiffness of the sheets, it is much easier to wind narrow sheets than wide ones. By heating the sheets, 15
- 20 as they are wrapped about the core, they will contract upon cooling and maintain a very strong mechanical construction. By maintaining a high temperature of the sheet as it is rolled in place, stiffness in the sheet is reduced and the hardening effect due to the rolling is greatly reduced. With this method, the ratio of magnetic material to insulation may be materially increased as the air spaces will be greatly reduced. 25
- 30 After the wrapping operation, the sheets comprising the core are clamped or bound in position until after the annealing and impregnating operations have been completed, so as to prevent loosening of the sheets. 35
- Where it is desired to obtain a particularly tight construction, the center portion is maintained at a lower temperature during the winding operation so as to provide a substantially smaller core during the forming of the 40 hot sheet. This cooling may be applied to the sheet being wrapped into position after it is partially wound. The cooling may come about naturally or may be brought about by any suitable cooling means such as an air blast 45 or the application of a cooled surface. Where the cores are wound upon tubular members, the cores may be readily kept cool by the passage of air or liquid through the tubes. The wrapped type of construction which I 50 have devised for transformer cores offers material advantages for magnetic circuits of various types, as the cores may be readily made from strip or sheet material, frequently, without loss. Expensive dies are also eliminated. 55
- In the form of the invention shown in Figs. 2 and 3, the sheet metal 27 may be wound as explained above. The magnetic material may be wound with but a single turn between 60 adjacent layers of insulating material or several layers of magnetic material may be placed together with one or more insulating zones separating the several stacks of magnetic material as desired. The usual method is to wrap the various sheets with their insu-

lation upon a mandrel. With this type of magnetic core, the magnetic flux has a path largely through the magnetic material but also through the insulating layer. Since the area for the air path is very large, the reluctance of the magnetic circuit may be made low by maintaining a small thickness for the insulation. The characteristics of this construction can be used to advantage in some cases as the permeability of the magnetic path is different from that where the path is entirely of iron or magnetic material. Where it is desired, the magnetic reluctance can be further reduced by placing the magnetic clips 70 over the ends of the sheets, as shown in the 75 drawing, which provides a path between the inner and outer turns. The magnetic circuit provided by the clips may be formed in several different ways, providing, however, a short-circuit turn is not formed. 80

In place of the magnetic clips 28, a ribbon 29 may be used for wrapping the core, as shown in Figs. 4 and 5 or cup shape rings 30 which do not set up a short-circuit turn may be used, as shown in Fig. 6. If desired, several sets of magnetic clips or return paths 90 may be used at intermediate points in the winding. Where a ribbon winding is used it should be provided with one or more insulating joints as shown at 32 and 33, to prevent 95 the ribbon from forming a closed electrical conductor. Since the voltage across the joint is not very high, the ends of the magnetic ribbon may be brought close together or overlapped so as to permit ready passage of the 100 magnetic flux across the insulation.

The types of cores just described may be used to advantage where the cores are desired for transformers having appreciable outputs as it may be desirable in such cases to 105 provide cooling ducts in cores of this kind. The increased space due to the cooling duct tends to increase materially the reluctance of the magnetic circuit unless the magnetic clips or by-passes are used. These clips can be 110 used, not only to provide necessary separation for the cooling passages but to reduce the reluctance of the magnetic circuit. Several cores having different diameters may be placed together concentrically with sufficient 115 space between to provide the cooling slots as shown at 31 in Fig. 7 or, if desired, the return magnetic path may be interposed at different points in the magnetic sheets as they are wound up. 120

By the use of the magnetic clips as illustrated in the drawing, the magnetic characteristics of the current transformer may be materially varied, owing to the differences in length of magnetic paths, particularly where 125 there is considerable difference between the inner and outer diameters of the core and the return magnetic paths are placed intermediate the inner and outer surfaces of the core. This is due to the fact that a given flux will be 130

developed with a much less magnetomotive force near the center of the core where the effective length of the magnetic path is short than at the outer edge where the path is considerably longer. This will tend to smooth out irregularities due to the saturation characteristic of the iron. This method is used to advantage in the construction of series or shunt impedances for the correction of the current transformer characteristics, as disclosed in my previous application Serial Number 433,921.

The method of construction comprising the winding of several sheets with insulation between groups, together with a return magnetic path, can be used to advantage in the production of power and potential transformers as the construction results in a strong magnetic core of low cost. The magnetic core may be of any desired shape having, for instance, straight sides and oval ends or it may be rectangular in shape. By heating the iron or magnetic material as it is wound or wrapped in place, the contraction upon cooling will tend to cause a dense core of good mechanical strength. If the magnetic properties of the material are disturbed during the winding or wrapping operation, these may be materially corrected by subsequent annealing as previously described. The whole may be wrapped upon a core or hollow spool which can remain in position. In general, however, this spool should be made of a low resistance or non-magnetic material to cut down possible eddy currents. In some cases, by using a suitable hollow core mandrel, the magnetic circuit may be wound through coils which have been previously formed. This obviates the necessity of winding the coils after the core has been formed. In many cases, however, the coils may be readily wound or suitable spools or cores placed over the magnetic circuit, the equipment being similar in action to that used in taping or wrapping insulation, or in applying insulation to rings.

Any of the several types of cores shown may be used for reactance coils having a wide variation in the reluctance of the magnetic circuit. When the cores are used for reactance coils in which it is desired to incorporate the characteristics of an air gap in the magnetic circuit, a suitable winding is placed through and around the magnetic material. When the core is used for a current transformer in a bushing, the transformer winding is disposed around the axis of the core but when it is used for a reactance coil, the turns are in a plane parallel to the axis of the core and threaded through the opening in the core. This type of construction may also be used for a core in a transformer where it is desired to decrease the reluctance of the magnetic circuit, giving the core characteristics like that of a magnetic circuit containing an air gap.

With the construction shown, it is possible to make a strong magnetic core in which the reluctance of the magnetic circuit may be varied over a large range. At the same time, circular or rectangular cores may be formed with a loss of little or no material as the cores may be made from strip material. Where the cores are used for reactance forming the equivalent of a closed magnetic circuit, the type of construction makes it possible to change the magnetic flux characteristics in the core very materially.

Where the inner diameter of the core is small compared to the outer diameter, the shorter magnetic path adjacent the center will permit more flux for a given number of ampere turns than the longer path formed by the outer layers. By varying the inner and outer diameters, or the insulation between turns, or the magnetic shunts 34, 35 and 36, Fig. 7, the lines of force set up for a given magnetizing force may be made to vary. If it is desired to cause an early saturation in a portion of the core and a delayed saturation in another portion of the core, this is readily brought about by properly regulating the factors just named. This is illustrated by Fig. 7. By using insulation between layers of magnetic material and using shunt magnetic paths 35, together with a shorter length of magnetic path, a given number of ampere turns affecting the core would build up a higher flux per given area in the inner portion of the core than in the outer layers, particularly if part or all of the shunt paths 34 and 36 are removed and the insulation between turns increased.

With the construction shown, it is possible to give improved magnetic characteristics for adjusting impedance or reactance coils used for correcting phase angle, ratio of current transformers or in making current limiting reactances. The type of construction makes it possible to build a current limiting reactance of high mechanical strength and good insulation for limiting the short-circuit currents in buses or feeder circuits. High mechanical strength with the desirable magnetic properties makes it possible to form current limiting reactors for suitable voltages where the reactors are oil insulated for insertion in feeder circuits or in the neutrals of transformer banks.

I claim:

1. A magnetic core for electrical apparatus comprising a sheet of magnetic material wound in convolutions, and a retainer of magnetic material, spanning the edges of a plurality of convolutions at the end of said core and in contact with said edges for holding said convolutions together, said retainer having a radially extending portion forming a return path for magnetic lines of force.

2. A magnetic core for electrical apparatus comprising a sheet of magnetic material

- wound to form a plurality of convolutions, certain of said convolutions being spaced apart providing air spaces therebetween.
3. A magnetic core for electrical apparatus comprising a sheet of magnetic material wound to form a plurality of convolutions, and holding members for securing said convolutions together, said holding members having portions thereof disposed between certain of said convolutions and separating said convolutions to form air spaces therebetween.
4. The method of forming a magnetic core for electrical apparatus comprising the steps of winding or wrapping sheet material to form a plurality of convolutions, securing the convolutions together, annealing the core thus formed; impregnating the core with insulating material and curing or baking the impregnated core.
5. The method of forming a magnetic core comprising the steps of wrapping or winding sheet material together while heated and permitting the core thus formed to cool to cause the parts to contract.
6. The method of forming a magnetic core comprising the steps of winding or wrapping sheet material together, the outer wrapper being heated during the forming operation while the inner portion of the core is cooled, the core being permitted to cool after forming so that the outer wrappings will contract upon the inner portion of the core.
7. A magnetic core comprising a plurality of thin sheets of magnetic material laid together and wound upon a common axis, the inner edges of adjacent sheets being circumferentially spaced from each other.
8. A magnetic core comprising a plurality of layers of magnetic sheet material encircling a common axis, and insulation disposed between some of said layers while other layers are in direct electrical and mechanical contact.
9. A magnetic core comprising a plurality of layers of magnetic sheet material wound about a common axis, said material being disposed in groups each comprising a plurality of sheets placed together in contact with one another, and insulating material separating said groups.
10. A magnetic core comprising a plurality of layers of magnetic sheet material wound about a common axis, insulating material separating some of said layers and some of said layers being spaced apart to provide air passages between said layers.
11. A magnetic core comprising a plurality of sheets of magnetic material laid together to form a stack and wound about a common axis, the inner edges of adjacent sheets being circumferentially spaced from each other, and insulating material separating the convolutions of said stack.
12. A magnetic core comprising a plurality of layers of magnetic sheet material wound upon a common axis, some of said layers being spaced apart to provide air passages between said layers, and magnetic material disposed radially at the end of said core to form a return path for magnetic flux 70 radially overlapping the end edges of the layers of magnetic material forming said core.
13. A magnetic core comprising a plurality of layers of magnetic sheet material wound about a common axis, clips of magnetic material extending radially of said core at the ends thereof and overlapping some of said layers, the ends of said clips being extended between some of said layers to space said layers apart.
14. A magnetic core formed of a plurality of layers of magnetic sheet material wound about a common axis, certain layers of said core being spaced apart to provide air passages between said layers, and magnetic material bridging the space between said layers to provide a return path for magnetic flux 80 across said space.
15. A magnetic core comprising a plurality of sheets of magnetic material laid together and wound about a common axis, the inner edges of adjacent sheets being circumferentially spaced from each other, insulation separating the layers of the core thus formed into groups having a plurality of layers in each group, some of the adjacent layers of said core being spaced apart providing air space therebetween, and magnetic material disposed radially of said core adjacent the end edges of said layers and forming a return path for magnetic flux. 90
16. A magnetic core for electrical apparatus comprising a plurality of superimposed layers of magnetic material, each layer including a strip of said material wound helically about an axis, the joints between adjacent convolutions in each layer being staggered relative to the joints in the adjacent layers. 100
17. A magnetic core for electrical apparatus comprising magnetic material in strip form and helically wound about an axis in a plurality of layers, the joints between the convolutions in adjacent layers being staggered, and binding material for holding the convolutions together. 110
18. A laminated magnetic core for electrical apparatus, and means for decreasing the reluctance of the path of the magnetic flux in said core comprising a strip of magnetic material extending transverse to the laminations of the core and in a direction to form a return path outside of said laminations for the flux in the magnetic circuit of the core. 120
19. A laminated magnetic core having adjacent laminations thereof insulated from one another, and means for decreasing the reluctance of the magnetic path of said core comprising a strip of magnetic material ex- 125
- 130

tending transverse to the laminations of the core and in a direction to form a return path outside of said laminations for the flux in the magnetic circuit of the core.

- 5 20. A laminated core for electrical apparatus having adjacent laminations insulated from one another, and means for holding said laminations together and for decreasing the reluctance of the magnetic circuit in said core,
10 said means comprising a clip of magnetic material extending transverse to the laminations at the edges thereof and having portions holding said laminations together, said clip having contact with said laminations
15 and extending in a direction to form a return path outside of said laminations for the flux in the magnetic circuit of the core.

In testimony whereof I have signed my name to this specification this 2nd day of
20 January A. D. 1931.

ARTHUR O. AUSTIN.
